CLAIM

The ornamental design for the lighted bollard, as shown and described.

DESCRIPTION

FIG. 1 is a front elevation view of the lighted post of the present invention, which is identical to the rear elevation view, wherein the dotted lines showing additional construction details are for illustrative purposes only and do not form any part of the claimed design;

FIG. 2 is a left side elevation view of the post of FIG. 1; FIG. 3 is a right side elevation view of the post of FIG. 1; FIG. 4 is a top plan view of the lighted post of FIG. 1, the bottom plan view of which forms no part of the invention; FIG. 5 is front elevation view of another embodiment of the lighted post of the present invention, which is identical to the rear elevation view, wherein the dotted lines showing additional construction details are for illustrative purposes only and do not form any part of the claimed design;

FIG. 6 is a left side elevation view of the lighted post of FIG. 5;

FIG. 7 is a right side elevation view of the lighted post of FIG. 5;

FIG. 8 is a top plan view of the lighted post of FIG. 10, the bottom plan view of which forms no part of the invention; FIG. 9 is a front elevation view of another embodiment of the lighted post of the present invention, which is identical to the rear elevation view, wherein the dotted lines showing additional construction details are for illustrative purposes only and do not form any part of the claimed design;

FIG. 10 is a left side elevation view of the lighted post of FIG. 9;

FIG. 11 is a right side elevation view of the lighted post of FIG. 2; and,

FIG. 12 is a top plan view of the lighted post of FIG. 9, the bottom plan view of which forms no part of the invention.
